HEAT EXCHANGE APPARATUS

Charles H. Leach, Roselle, N. J.

Application September 18, 1937, Serial No. 164,458

11 Claims. (Cl. 257—28)

This invention relates to heat exchange apparatus and particularly to heat exchange apparatus used in refining petroleum oil.

It is an object of the invention to provide improved heat exchange apparatus operating at a high rate of efficiency and in which tube erosion and loss of pressure are reduced to a minimum.

My invention relates particularly to heat exchange apparatus in which heat exchange tubes are connected to headers and are encased in a shell, and in which heat is exchanged between fluids. One of the fluids is circulated inside the tubes and the other fluid, usually in the form of vapor, is circulated around the tubes inside the shell. At the point of admission of the vapor into the shell the tubes are usually subjected to considerable erosion or wear due to the impact of the vapor particles against the tubes, and also there is considerable localized pressure drop in the vapor at this point.

It is an object of the invention to overcome the difficulties heretofore encountered in heat exchange apparatus of this character and to provide improved heat exchange apparatus in which tube erosion and pressure loss is reduced to a minimum.

It is a further object to provide improved heat exchange apparatus as set forth above, of economical construction and in which the heat exchange tubes are readily accessible for inspection and cleaning, and in which guides are provided inside the shell for determining the position of the floating heads and so as to permit the ready insertion of the floating heads and heat exchange tubes into the shells and their removal therefrom.

For a fuller understanding of the invention reference should be had to the accompanying drawings, in which:

40 Figure 1 is a longitudinal sectional view of heat exchange apparatus embodying my invention;

Fig. 2 is an elevation partially in section in the direction of the arrows on the line 2—2 of Figure 1;

Fig. 3 is a sectional view in the direction of the arrows on the line 3—3 of Figure 1;

Fig. 4 is a sectional view in the direction of the arrows on the line 4—4 of Figure 1;

50 Fig. 5 is an elevation partially in section of the lower end of heat exchange apparatus embodying my invention and showing a modified type of shell and baffle construction, the tubes and floating heads being omitted for the sake of clarity;

Fig. 6 is a longitudinal sectional view with the central portion omitted, of the shell of heat exchange apparatus embodying my invention, showing another modified type of baffle construction, the heat exchange tubes and heads being omitted for the sake of clarity; and

Fig. 7 is a sectional view in the direction of the arrows on the line 7—7 of Fig. 6.

Heat exchange apparatus embodying my invention preferably comprises a fixed head 10, 10 floating heads 11 and 12, tube bundles 13 and 14 connected between the fixed and floating heads, and a shell 15 encasing the tube bundles and floating heads. In the accompanying drawings I have illustrated a pair of floating heads and tube bundles which give very satisfactory results, but it is to be understood that the number of floating heads and tube bundles may be varied. The fixed and floating heads and the tubes form a passage for one of the fluids, preferably the cooling fluid, while the shell encases a passage for the other fluid which extends between and around the heat exchange tubes.

The fixed head may be of any desired construction. Thus, as shown, it may comprise an annular member 16 provided with a pair of integral partitions 17 and 18 which provide the fluid chambers 19, 20 and 21. A tube sheet 22 is suitably secured to the annular member as by means of bolts 23 passing through the tube sheet and through a flange formed around the lower edge of the annular member. So as to enclose the chambers 19, 20 and 21 a cover member 24 is suitably secured to the upper end of the annular member as by means of bolts 25 passing through the cover member and through a flange formed around the upper surface of the annular member. So as to secure a tight sealing engagement between the annular member and the cover member and the annular member and the tube sheet, an annular rib seated in a groove may be provided at each joint as indicated at 26 and 27 and in addition, of course, gaskets may be employed at these points.

So as to provide an inlet and an outlet for the cooling fluid I provide the annular member 16 with a pair of nozzles 29 and 30 which communicate with the chambers 19 and 21 respectively. The fluid may thus be introduced into the chamber 19 through the nozzle 29 and after circulating through the heads, as will be later explained, will be withdrawn from the chamber 21 through nozzle 30.

The floating heads 11 and 12 are preferably of similar construction, each being formed with a

- tube sheet 31 having a cover member 32 secured thereto by means of bolts 33, both the tube sheet and cover member being formed with side walls so as to provide an enclosed chamber 34. The tubes of the bundles 13 and 14 are expanded into openings formed in the tube sheets of the floating and fixed heads so that the inside of the tubes communicate with the chambers formed in the heads.
- 10 The tubes of bundle 13 are connected at their lower ends with the floating head 11 so as to communicate with the chamber formed therein and at their upper ends are connected with fixed head 10 so that some of the tubes communicate with chamber 19 and the remaining tubes communicate with chamber 20. Similarly, the tubes of the bundle 14 are connected to the floating head 12 at their lower ends, so as to communicate with the chamber therein, and at their upper ends with fixed head 10, so that some of the tubes communicate with the chamber 21, while the remaining tubes communicate with the chamber 20. In this way a continuous and unobstructed fluid passage is provided by means of the fixed head, the tubes and the floating heads. Thus the fluid may be introduced through the nozzle 29 into the chamber 19, whence it travels through the tubes communicating therewith to the floating head 11, and from there returns through the remaining tubes of bundle 13 to the chamber 20 in the fixed head. The fluid then travels through the tubes of bundle 14, which communicates with chamber 20, to the floating head 12, and then through the remaining tubes of bundle 14 into chamber 21 and out through nozzle 30. Another fluid passage, encased by shell 15, is provided around the outside of the tubes so that heat may be exchanged between the fluid inside and outside the tubes.
- 40 The structure heretofore described may be the same in each form of my invention. The shell and baffle structure shown in the first four figures of the drawings will now be described.
- 45 The shell 15 comprises a cylindrical portion 36 provided with a flange at its upper end, indicated at 37, which is connected by means of bolts 23 to the fixed head. The cylindrical portion 36 is preferably spaced a short distance from the outer tubes in the bundles 13 and 14 and extends from the fixed head to a short distance above the floating heads, where it connects with an adapter which may take the form of a tapered collar portion 38 at the end of which an enlarged bell 39 is formed. The lower end of the enlarged bell 39 is 50 enclosed by means of a dome or cap 40. Each of the portions of the shell indicated at 36, 38, 39 and 40 may be formed separately and welded together at points 41, 42 and 43. However, this is merely a matter of construction and two or more of the parts may be formed in one piece if desired.
- 55 So as to provide an inlet and outlet for the vapor which is circulated inside the shell, nozzles 44 and 45 are formed in the bell 39 at opposite sides thereof. The relative sizes of the tube bundles, floating heads and shell are preferably such that the nozzles 44 and 45 communicate with the interior of the shell at a point beneath the floating heads 11 and 12. Due to the fact that the nozzles 44 and 45 communicate with the enlarged area enclosed within the bell 39 beneath the tube bundles, the entering vapor does not impinge against the tubes, and accordingly, tube erosion at this point is eliminated. Also, the localized pressure loss usually occurring at this point is reduced to a minimum due to the enlarged chamber

inside the bell. These advantages result from the fact that not only is an enlarged area provided by the bell, but also the floating heads and tubes have been removed from the point at which the nozzle communicates with the interior of the shell. The floating heads and tube bundles may be extended below or to the level of the nozzles and the advantages set forth above will still be obtained but to a lesser degree due to the enlarged chamber provided by the bell.

10 So as to provide a double-pass vapor passage extending longitudinally of the tubes a longitudinal baffle 46 is positioned in the shell between the floating heads. The baffle preferably extends from the bottom of the shell to a point adjacent the fixed head, being preferably welded along the edges to the dome 40, bell 39, collar 38, and cylindrical section 36. It may be formed in one piece, in which event it must be inserted inside the shell before the dome 40 is welded over the lower end of the bell, or if desired, it may be formed in sections corresponding to the shell section, each section of the baffle being welded to its respective section of the shell and abutting end to end when the shell sections are assembled as shown in Figs. 1 and 2. When the shell sections are welded together the sections of the baffle may be welded together to form an integral baffle as shown in Fig. 1.

15 So as to provide communication between the two passes formed by the baffle 46, the baffle is preferably provided adjacent its upper end with apertures 47. Thus a complete vapor passage is provided. The vapor may be introduced into the shell through the nozzle 44, whence it will travel 20 upwardly in contact with the tubes of tube bundle 14, through the apertures 47, downwardly in contact with the tubes of tube bundle 13 and out through the nozzle 45.

25 The collar 38 or other adapter should be so 30 formed as to direct the vapor into contact with the tubes, but so as to prevent too sharp an impact which would result in excessive erosion. Thus the taper of collar 38 is relatively gradual. I have found that a more even distribution of 35 the vapor and a more efficient and uniform transfer of heat is obtained by spacing the floating heads away from the central baffle 46, and to accomplish this I provide a pair of guide ribs 48 at each side of the baffle and positioned so as to engage the inner surface of the floating heads 11 and 12 so as to cause them to be spaced a slight distance away from the central baffle. When the floating heads are thus positioned at a spaced distance from the central baffle their 40 outer edges will be located beneath the side wall of the cylindrical portion 36 of the shell. So as to prevent any interference between the floating heads and shell, where it is desired to remove the tubes and floating heads from the shell for inspection, I also provide guide ribs 49, preferably three in number, at each side of the shell, which are welded to the inside of the collar 38 and the bell 39 for guiding the floating heads.

45 The guide ribs 48 and 49 are preferably of such 50 a size and shape as to provide a slight clearance between the floating heads and ribs so as to permit the ready insertion of the tubes and floating heads into the shell to the position shown in Fig. 1 and also their removal therefrom. Due to the 55 guide ribs just described, the bolts 23 may be removed and the tubes and floating heads may be withdrawn from the shell without any danger of interference between the floating heads and the wall of the cylindrical portion 36 of the shell.

The guide ribs also permit the tube bundles and floating heads to be located in a more central position when in use thereby providing a space between the baffle and the floating heads as well as between the shell wall and floating heads.

As the vapor passes through the passage in the shell in contact with the tubes it is progressively cooled and a portion thereof condenses and drops into the dome 40 of the shell. Due to differences in temperature, condensates of different character will form on the two sides of the baffle 46 and separate bleeds or drains are provided on the two sides of the baffle. The drains are indicated at 50 and 51 respectively, the drain 50 being positioned beneath the tube bundle 14 and having a nozzle 52 connected thereto, and the drain 51 being positioned beneath the tube bundle 13 and having a nozzle 53 connected thereto.

So as to support the heat exchange apparatus in the desired position, as illustrated, with the fixed head at the top and with the enlarged bell and floating heads depending downwardly, suitable supporting lugs 54 may be formed on the cylindrical portion of the shell as shown most clearly in Fig. 2.

In using apparatus of the character just described a suitable cooling fluid such as crude oil, water or the like, is introduced through nozzle 29 and is circulated through the heat exchange tubes, floating heads and chambers formed in the fixed head, and is then withdrawn through nozzle 30.

The hot petroleum vapor which is to be cooled or condensed is introduced through nozzle 44. It will be seen that the vapor from nozzle 44 enters the enlarged space or chamber beneath the floating head 12, thereby eliminating direct impingement of the vapor particles against the heat exchange tubes, and also minimizing pressure drop at this point. The vapor becomes equally distributed throughout the chamber and then passes upwardly through the space provided by the guide ribs on all sides of the floating head 12, where it is directed inwardly into contact with the tubes of tube bundle 14. Due to the relatively gradual taper of the collar 38 sharp impact between the vapor particles and the tubes is prevented. However, because of the progressive restriction of the passage, contact between the vapor particles and tubes is insured. The vapor passes upwardly in contact with the tubes of the bundle 14, thence through the apertures 47 and downwardly in contact with the tubes in bundle 13 into the chamber formed in the bell beneath the tubes and thence outwardly through the nozzle 45. It will be seen that the cooling fluid and the vapor travel in a general direction of counter-flow. As the vapor is progressively cooled through its contact with the heat exchange tubes as it travels through the vapor passage, portions thereof are condensed, the heaviest oils condensing first, adjacent the beginning of the passage, and the lighter oils condensing later, against the end of the passage. The condensed oils flow downwardly due to gravity and finally are deposited upon the dome 40 and pass outwardly through the drains 50 and 51, the condensate coming through the drain 50 being of a somewhat heavier character than the condensate coming through the drain 51.

Referring now to the modified form of shell and baffle shown in Fig. 5, it will be seen that some of the sections of the shell, instead of being welded together, are provided with bolting connections which permits of the disassembling of

the shell. Thus, the cylindrical section 36 is illustrated as being provided with a flange 55 at its lower end, and the collar 38 is provided with a flange 56 at its upper end, the two flanges being bolted together by means of bolts 57. The collar 38 and bell 39 are welded together as in the first form of my invention. However, the dome 40 is provided with a flange 58 at its upper end, and the bell 39 has a flange 59 at its lower end, the two flanges being secured together by means of 10 bolts 60. In this form of my invention the baffle 46 is preferably formed in three separate sections abutting end to end, corresponding to the shell sections. The three sections of the baffles are indicated at 61, 62 and 63, the section 61 being welded to the inside of the cylindrical portion 36 of the shell, the section 62 being welded to the inside of the collar 38 and bell 39, and the section 63 being welded to the inside of the dome 40. When the shell is thus formed in separable sections the supporting lugs 54 are preferably secured to the bell 39 as indicated. In this way the upper and lower sections of the shell may be removed without the necessity of disconnecting nozzles 44 and 45 from the inlet and outlet pipes. 25

In the form of my invention shown in Fig 6 the shell 50 is formed similarly to the shell in the first form of my invention. The baffle 46 however, is of somewhat different construction. Thus, the baffle is formed of a rectangular plate 65 of uniform width from top to bottom, and which extends from adjacent the top of the shell to a short distance from the bottom thereof. The plate 65 is connected as by means of bolts 66 to wing-like projections 67 projecting from the bottom of the shell and from the opposite sides thereof and extending from top to bottom. The wing-like projections 67 are welded to the different sections of the shell and it will be seen that they vary in width so as to compensate for the taper of 40 the collar and the greater width of the bell portion of the shell. In this form of my invention the plate 65 of the baffle may be conveniently removed from the shell by removing the bolts 66. The forms of my invention shown in Figs. 5, 6 and 45 7 likewise are provided with guide ribs 48 and 49 similar to those provided in the first form of my invention.

As has previously been stated, the tubes, floating heads and shell are preferably of such a size 50 that the floating heads are positioned above the nozzles 44 and 45 and the most satisfactory results are obtained when the floating heads are thus positioned. However, the floating heads may extend downwardly to a point adjacent the 55 nozzles 44 and 45 and a reduction in erosion and localized pressure drop will also be obtained due to the enlarged space or chamber provided by the bell. In Fig. 6 the guides 48 are illustrated as extending down to a point adjacent the lower 60 level of the nozzles 44 so as to permit relatively longer tube bundles to be employed in which the floating heads will extend downwardly to this point. However, the guide ribs 48 and 49 in this form of my invention may be located similarly to 65 the guide ribs of the first form of my invention. The tubes, floating heads, fixed head and the connections between the floating heads and the fixed head in the forms of my device shown in Figs. 5, 6 and 7, are similar to the arrangement 70 shown in the first form of my invention, and the operation of the apparatus is likewise similar.

It will be appreciated from the accompanying drawings and the foregoing description that I have provided improved heat exchange apparatus

- which is specially suited for the refining of petroleum oil, which will operate at a high rate of efficiency, and in which tube erosion and undesirable loss of pressure are reduced to a minimum
- 5 It should be understood that modifications may be made in the illustrated and described embodiments of my invention without departing from the invention as set forth in the accompanying claims.
- 10 I claim:
1. Heat exchange apparatus comprising a fixed head, a floating head spaced from the fixed head, heat exchange tubes connected between the fixed and floating heads so as to form a fluid passage, a shell enclosing the tubes and the floating head, and a baffle inside the shell extending from the end of the shell adjacent the floating head to adjacent the opposite end so as to form a vapor passage between and around said tubes, said shell having a cylindrical portion spaced a short distance from the heat exchange tubes and extending from the fixed head to adjacent the floating head, and an enlarged bell portion positioned adjacent the floating head and connected by means of a tapered collar to the cylindrical portion, the bell portion being formed with a dome at the end thereof and with a vapor inlet nozzle at the side thereof and communicating with the inside of the shell on one side of the baffle.
  2. Heat exchange apparatus comprising a fixed head, a plurality of floating heads spaced from the fixed head, heat exchange tubes connected between the fixed and floating heads so as to form a fluid passage, a shell enclosing the tubes and floating heads, and a baffle inside the shell for forming a vapor passage extending between and around the tubes, the shell having an enlarged portion of greater cross sectional area adjacent the floating head and having vapor inlet and outlet nozzles formed in the enlarged portion.
  3. Heat exchange apparatus comprising a fixed head, a plurality of floating heads spaced from the fixed head, heat exchange tubes connected between the fixed and floating heads so as to form a fluid passage, a shell enclosing the tubes and floating heads and releasably secured to the fixed head, a baffle secured inside the shell for forming a vapor passage extending between and around the tubes and positioned in a plane between two adjacent floating heads so that the floating heads and tubes may be removed from the shell without interference from the baffle, said shell being formed with an enlarged bell portion adjacent the floating heads and with vapor inlet and outlet nozzles formed therein so as to communicate with the interior of the shell on opposite sides of the baffle, and means for spacing the floating heads from the baffle and for maintaining them in that position while in use.
  4. Heat exchange apparatus comprising a fixed head, a plurality of floating heads spaced from the fixed head, heat exchange tubes connected between the fixed and floating heads so as to form a fluid passage, a shell enclosing the tubes and floating heads and releasably secured to the fixed head, a baffle secured inside the shell for forming a vapor passage extending between and around the tubes and positioned in a plane between two adjacent floating heads so that the floating heads and tubes may be removed from the shell without interference from the baffle, said shell being formed with an enlarged bell portion adjacent the floating heads and with vapor inlet and outlet nozzles formed therein so as to com-

municate with the interior of the shell on opposite sides of the baffle, and guide means mounted on the inside of the shell adjacent the point of connection between the enlarged bell portion and the remainder of the shell for facilitating the insertion and removal of the floating heads.

5. Heat exchange apparatus comprising a fixed head, a plurality of floating heads spaced from the fixed head, heat exchange tubes connected between the fixed and floating heads so as to form a fluid passage, a shell enclosing the tubes and floating heads and releasably secured to the fixed head, a baffle secured inside the shell for forming a vapor passage extending between and around the tubes and positioned in a plane between two adjacent floating heads so that the floating heads and tubes may be removed from the shell without interference from the baffle, said shell being formed with an enlarged bell portion adjacent the floating heads and with vapor inlet and outlet nozzles formed therein so as to communicate with the interior of the shell on opposite sides of the baffle, and guide members formed on opposite sides of the baffle adjacent the enlarged bell portion of the shell for engaging the floating heads and positioning them a spaced distance from the baffle.

6. Heat exchange apparatus as specified in claim 5 in which additional guide members are formed on the inner surface of the bell portion of the shell to facilitate insertion and removal of the floating heads.

7. Heat exchange apparatus comprising a fixed head, heat exchange tubes depending downwardly from the fixed head, a floating head secured to the lower end of the heat exchange tubes so that the fixed and floating heads and heat exchange tubes form a fluid passage, a shell secured to the fixed head and enclosing the heat exchange tubes and floating head, and a baffle inside the shell extending from the end of the shell adjacent the floating head to adjacent the opposite end so as to form a vapor passage the shell having a cylindrical portion extending from the fixed head to a short distance above the floating head, and an enlarged bell portion of greater cross sectional area than the cylindrical portion connected to the cylindrical portion by means of a tapered collar and extending downwardly below the floating head, said bell portion being formed with a dome at the lower end thereof and having a vapor inlet nozzle formed therein at a point below the floating head.

8. Heat exchange apparatus comprising a fixed head, a plurality of floating heads positioned beneath the fixed head, heat exchange tubes connected between the fixed and floating heads so as to support the floating heads and so that the fixed and floating heads and the heat exchange tubes form a continuous fluid passage, a shell secured to the fixed head and enclosing the floating heads and heat exchange tubes, said shell having a portion of uniform cross sectional area extending from the fixed head to adjacent the floating heads and having an enlarged bell portion adjacent the floating heads in which inlet and outlet vapor nozzles are provided, and a baffle extending longitudinally of the shell from the bottom thereof to adjacent the fixed head so as to provide a vapor passage inside the shell extending between and around the heat exchange tubes.

9. Heat exchange apparatus as set forth in claim 8, in which the enlarged bell portion extends below the floating heads, and the inlet and

outlet nozzles are formed therein at points below the floating heads.

10. Heat exchange apparatus as specified in claim 8, in which guide means are provided for 5 spacing the floating heads from the baffle, and in which additional guide means are also provided in the interior of the bell portion to facilitate the insertion and removal of the floating heads.

11. Heat exchange apparatus comprising a 10 fixed head, heat exchange tubes depending downwardly therefrom, a plurality of floating heads secured to the lower ends of the heat exchange tubes so that the fixed and floating heads and heat exchange tubes form a continuous fluid passage, a 15 shell removably secured to the fixed head and enclosing the heat exchange tubes and floating heads, said shell having a cylindrical portion extending from the fixed head to a short distance above the floating heads and an enlarged bell 20 portion of greater cross sectional area than the

cylindrical portion extending below the floating heads and connected to the cylindrical portion by means of an adapter, said bell portion being formed with a closure dome at its lower end and with vapor inlet and outlet nozzles at opposite sides at points below the floating heads, a longitudinal baffle extending from the bottom of the shell to adjacent the fixed head so as to form a vapor passage interiorly of the shell between and around the heat exchange tubes, guide members 10 formed on the two sides of the longitudinal baffle adjacent the bell portion for engaging the floating heads and positioning them a spaced distance from the baffle, and additional guide members formed on the inside of the shell to facilitate the 15 insertion and removal of the floating heads, said dome being formed with separate condensate drains on the two sides of the longitudinal baffle.

CHARLES H. LEACH. 20
